UNITED STATES PATENT OFFICE.

CHARLES M. KIMBALL, OF TOLEDO, OHIO, ASSIGNOR OF TWO-THIRDS TO E. T. KEYES, OF SAME PLACE, AND PATRICK DOWLING, OF HOLLAND, OHIO.

WATER-ELEVATOR.

SPECIFICATION forming part of Letters Patent No. 318,915, dated May 26, 1885.

Application filed May 10, 1884. (No model.)

To all whom it may concern:

Be it known that I, CHARLES M. KIMBALL, of Toledo, in the county of Lucas and State of Ohio, have invented certain new and useful

5 Improvements in Water-Elevators, of which the following is a specification, reference being had to the accompanying drawings, and to the letters of reference marked thereon.

My invention has special reference to an apparatus to be located on lines of railroad having a tank into which water is to be elevated for supplying the tanks of locomotive-tenders, or for other purposes for which water is required upon lines of railroad.

15 The invention relates to means whereby the water is elevated from a well or other source of supply at or near the base of the tank through the medium of a vacuum or partial vacuum formed within a close vessel or vacuum-chamber situated near the water-tank and connected therewith by a valved pipe, said vacuum-chamber being adapted for connection with the boiler of a locomotive or other steam-generator by a pipe provided with a 20 suitable valve or cock. The vacuum-chamber has connection with the cistern or other water-supply by means of a pipe having an automatically-acting valve adapted to seat against the pressure within the vacuum-tank and to 25 open under the influence of atmospheric pressure without said chamber. The vacuum-chamber is placed at a height less than thirty-two feet above the cistern or source of supply, so that the water is forced therein under the ordinary conditions. The tank to which the water is forced from the vacuum-chamber is 30 filled by the action of steam-pressure within the vacuum-chamber, the water previously lifted to the vacuum-chamber by atmospheric

35 pressure being forced from said chamber to the water-tank by the steam acting above the surface of the water in the vacuum-chamber. The pipe connecting the vacuum-chamber with the water-tank is provided with an automatically-acting valve opening upward into the water-tank by steam-pressure exerted within the vacuum-chamber, and closing by atmospheric pressure against the vacuum created in said chamber.

40 In the accompanying drawings, Figure 1 is

an elevation, partly in section, of my improved apparatus. Fig. 2 is a plan of the same.

Similar letters of reference indicate similar parts in both views.

A represents a locomotive standing upon 55 the track *a a*.

B is the tank to which the water is to be elevated, the tank being supported by the timbers *b* upon the bank *c* at the side of the road-bed. The arrangement of the tank with 60 reference to the track is immaterial, provided that it be such as to allow the convenient approach of the locomotive to a point contiguous to it.

C is the vacuum-chamber, communicating, 65 by means of a pipe, *c'*, with the cistern or water-supply D. The upper end of the pipe *c'* is provided with a cage, *c''*, in which is placed an upwardly-opening valve, *c'''*.

From the lower part of the vacuum-chamber 70 runs a pipe, *d*, connecting with the lower part or floor of the water-tank B. The upper end of the pipe *d* is also provided with a cage, *d'*, in which is located an upwardly-opening valve, *d''*.

The tank B may be open at its top, or closed by a suitable cover or lid. The tank B is provided with a neck or delivery-pipe, *e*, to which the hose or flexible connection *f* is applied, 75 it being adapted to lead to the tender of a locomotive, or to discharge water from the tank in a convenient manner.

The upper part of the vacuum-chamber C is provided with a pipe, *g*, having a cock or valve, *g'*. The outer end of the pipe *g* is furnished 80 with a joint or connection, *g''*, by means of which the pipe *g* can be conveniently attached to a pipe leading from the steam-space of the locomotive-boiler.

If desired, the pipe *g* may be made flexible 85 or jointed, whereby to facilitate the connection of the pipe with the locomotive-boiler.

The operation is as follows: Connection having been made between the vacuum-chamber C and the steam-space of the locomotive-boiler 90 by opening the cock *g'*, air is forced from the vacuum-chamber C through the pipe *d*, the valve *d''* within the tank B lifting from its seat, and the valve *c'''* within the vacuum-chamber 95 being forced downward to its seat. The cock 100

g' in the steam-pipe *g* is then to be closed and the steam within the vacuum-chamber *C* allowed to condense, forming a partial vacuum in the chamber, whereupon the valve *d''* in the 5 water-tank will close and the valve *c'''* within the vacuum-chamber will open by atmospheric pressure, and the vacuum-chamber thereupon fill with water. The vacuum-chamber having been filled with water, the cock *g'* is to be again 10 opened and steam again admitted to the vacuum-chamber, whereupon the pressure of steam will close the valve *c'''* within the vacuum-chamber *C* and open the valve *d''* within the tank, and the water will be forced from the 15 vacuum-chamber into the tank. This operation is successively repeated until the tank *B* has been filled with water.

If desired, a jet of cold water may be thrown into the vacuum-chamber *C* through the pipe 20 and nozzle *h* to facilitate the condensation of steam.

Steam may be supplied from any generator other than the locomotive-boiler.

A vacuum-gage may be applied to the vacuum-chamber to indicate the condition of the 25 vacuum.

In railroading it is well known that express-trains follow each other at very short intervals, and it is highly necessary that the operation of lifting the water shall be effected with the least possible delay. By this invention, 30 in which an elevated storage-tank is used, a passing locomotive in order to start the flow of water from the well or cistern need only 35 stop long enough to fill the vacuum-chamber with steam, which involves a delay of only a few moments. This engine may then proceed on its way, and the work of condensation beginning immediately thereafter water is lifted 40 to the vacuum-chamber during the absence of that engine for the use of the next train or three trains coming, for the vacuum-chamber

is of sufficient capacity to supply the deficiency in at least three tenders, and a sufficient supply is thus always kept on hand. It 45 is obvious that should the storage-tank be omitted, and the pipe from the vacuum-chamber lead directly to the tender, each engine would have to couple to the vacuum-chamber to force water therefrom to the tender, thus 50 causing delay; whereas by my invention an engine, by coupling with the vacuum-chamber, can first cause the lifting of a large body of water to said chamber, and afterward force the water up to the storage-tank for the use of the 55 next train or trains coming on, thus reducing delay in coupling up. After the steam has been used for forcing the water up to the storage-tank the condensation causes the vacuum-chamber to be again filled, and the water thus 60 elevated to the vacuum-chamber must be forced to the storage-tank by the next engine which couples with the vacuum-chamber.

This apparatus is simple and effective in operation, and will lift a large body of water 65 in a short time.

Having described my invention, I claim—

In an apparatus for elevating and storing water for delivery to the tanks of locomotive-tenders, the vacuum-chamber *C*, having the 70 pipe *c'*, valve *c'''*, and steam-pipe *g*, combined with the elevated storage-tank *B*, having the delivery-pipe *e*, pipe *d*, and valve *d''*, the whole arranged with relation to a railroad-track and a locomotive-boiler, substantially 75 as set forth.

In testimony whereof I have hereunto set my hand and seal this 25th day of April, A. D. 1884.

CHARLES M. KIMBALL. [L. S.]
